UNITED STATES PATENT OFFICE.

ALWIN J. SCHWARZENBACH, OF HASBROUCK HEIGHTS, NEW JERSEY, ASSIGNOR OF
ONE-HALF TO MICHAEL GOLD, OF NEW YORK, N. Y.

MACHINE FOR SHAPING ARTIFICIAL-FLOWER PETALS.

1,366,747.

Specification of Letters Patent. Patented Jan. 25, 1921.

Application filed June 25, 1919. Serial No. 306,563.

To all whom it may concern:

Be it known that I, ALWIN J. SCHWARZENBACH, a citizen of the United States, and resident of Hasbrouck Heights, in the county 5 of Bergen and State of New Jersey, have invented new and useful Improvements in Machines for Shaping Artificial-Flower Petals, of which the following is a specification.

This invention relates to improvements in 10 machines for shaping the petal portions of blanks employed in the manufacture of artificial flowers.

One of the objects of the invention is to provide simple and efficient mechanism for 15 simultaneously shaping a plurality of petals.

Another object of the invention is to provide means for curling, longitudinally scoring, and transversely crimping or crinkling an artificial flower petal.

20 Another important object of the invention is to provide means for simultaneously shaping a plurality of radially extending petals formed on a circular blank.

25 Another important object is to provide means adapted by a single operation to curl, longitudinally score, and transversely crimp or crinkle a plurality of petals simultaneously.

In the drawings, Figure 1 is a front elevation 30 of the machine;

Fig. 2 a side elevation thereof;

Fig. 3 a rear elevation thereof;

35 Figs. 4 to 7 diagrammatic views illustrating the operation of the machine.

Fig. 8 a detail sectional plan on the line 8—8 of Fig. 6;

Fig. 9 a plan view of one of the blanks; and

40 Figs. 10 and 11 detail views illustrating the combined scoring, curling and crimping action of the devices which act on the petals.

The frame 1 of the machine is of general 45 rectangular skeleton form. A blank support or disk-like table 2 is rigidly held to the reduced upper end of a vertical post 3 by a suitable locking screw 4, the reduced upper end of said post extending through the center of the disk and terminating flush with the upper face thereof. A blank-centering pin 5 is threaded into the upper end of the post. The post 3 is rotatably and slidably held in bearings 6 and 7 to permit raising and lowering of the blank support or table 2 through treadle mechanism hereinafter described, 55 and to permit rotation of the support 2 by

means of a handle 8 fixed to the support by suitable fastening devices 9. The blank support or table 2 is provided with a yieldable surface in the form of a removable disk 10 preferably made of soft rubber, the disk 10 having a central aperture through which the blank-positioning pin 5 extends. 60

An inverted drum or hollow circular scoring device support 11 is rigidly held to the frame 1 at the forward side of the machine 65 above the blank supporting table 2, said drum being formed with two lateral extensions 12 bolted or otherwise secured to the frame. A circular series of thirty-six bearing yokes 13 depend from the lower edge of 70 the drum 11 and a series of thirty-six scoring devices are pivotally supported at their upper ends in said yokes 13 to swing inwardly and upwardly along radially converging lines when the table or blank support is elevated, as hereinafter described. Each scoring device comprises a metallic 75 finger 14 pivotally held at its upper end by a pin 15 in the forked lower end of one of the yokes 13 and having a forked lower end in 80 which is journaled a metallic grooved scoring roller 16. The fingers 14 are curved inwardly, downwardly and outwardly, the lower ends of the fingers terminating within the vertical plane of the pivot points 15 85 thereof, so that when an upward pressure is exerted on the rollers 16 the fingers will swing inwardly and upwardly along converging lines. Each finger 14 is provided with an inwardly extending arm shoulder 90 or projection 17, the inner end of which is preferably rounded, as shown, and engages the downwardly and outwardly flaring bevelled or cam edge 18^a of a controlling disk 18.

The finger-controlling disk 18 is threaded 95 on the lower end of a vertically reciprocable rod or post 19 extending through a guiding or bearing sleeve 20 within the drum 11. The sleeve 20 is preferably cast integrally with the drum 11 and depends from the upper end of the drum axially thereof. The upper portion 19^a of the rod or post 19 is reduced in diameter and threaded. An adjusting and locking nut 21 is threaded on the upper end of the reduced portion 19^a of post 19, and a grooved collar 22 is also threaded on said portion 19^a of the post, the upper end of said collar engaging the lock nut 21 and the lower end thereof normally resting upon the top of the drum 11. It will be obvious 100 105 110

that by threading the nut 21 and collar 22 upwardly on the post the disk 18 will be lowered, and that by threading the nut and collar downwardly on the post the disk will be raised. By thus varying the normal position of the disk relatively to the pivots 15 of fingers 14, it will be obvious that the diameter of the circular series of rollers 16 may be increased or decreased to adapt the rollers to 10 shape blanks of different diameters. It will also be observed that the blank support 2 and the rubber cushion 10 may be readily removed and larger or smaller supports and cushions substituted therefor. The cushion 15 10 may be removed from table 2 and a harder or softer disk substituted therefor, to vary the action of the rollers 16, and, if desired, the blank may be placed directly upon the table without employing a cushion.

20 The blank supporting disk or table 2 is adapted to be raised and lowered by a treadle 23 keyed at its upper end to a rock shaft 24 which is journaled in suitable bearings 25 on the frame 1. A rearwardly and downwardly extending rock arm 26 is keyed on rock shaft 24 midway its ends, and the rear end thereof is pivotally connected by a pin 27 with the upper end of a vertical link 28. The lower end of link 28 is pivotally connected by a pin 29 with a lever 30 intermediate the ends of said lever. The lever 30 is fulcrumed at its rear end on a pivot pin 31 held in a suitable bearing 32 on the frame 1. The lever 30 normally extends 30 forwardly and downwardly and the forked forward end 30^a thereof engages in the grooved or reduced portion of a collar 33 fixed on the post or shaft 3 by a pin or key 34. A suitable spring 31 may be provided to assist in returning the treadle 23 to its normal position.

The scoring devices are adapted to be moved inwardly and upwardly, and downwardly and outwardly, independently of the 45 table 2, by means of a treadle 35 loosely pivoted at its upper end on rock shaft 24 between collars 36 and formed at its upper end with an integral rock arm 37 extending rearwardly and downwardly. The rear end 50 of rock arm 37 is pivotally connected with the lower end of a vertical link 38 by a pin 39. The upper end of link 38 is connected by a pivot pin 40 with the rear end of a rock arm 41 keyed on a rock shaft 42. The 55 rock arm 41 extends rearwardly and downwardly from shaft 42 and said shaft is journaled in suitable bearings 43 on the frame 1. A rock arm 44 is keyed on shaft 42 and extends rearwardly and downwardly therefrom. The rear end of rock arm 44 is connected by a pivot pin 45 with the lower end of a vertical link 46, and the upper end of link 46 is connected by a pivot pin 47 with a lever 48 intermediate the ends of said 60 lever. The lever 48 is fulcrumed at its rear

end on a pivot pin 49 held in suitable bearings 50 on the frame 1, and extends forwardly and downwardly from its fulcrum. Lever 48 is formed with a forked forward end engaging the grooved or reduced portion of collar 22 threaded on post 19. 70

The scoring devices are preferably heated to enhance the scoring, curling and crinkling action thereof and to assist in giving permanent form to the scored, curled and crinkled 75 petals. For heating the circular series of scoring devices I provide a circular burner ring 52 having apertures 53 therein for directing the flames upon the metal fingers 14 through which the heat is transmitted to 80 the scoring rollers 16. The burner ring 52 is fixed to the lower face of disk 18 and preferably partly countersunk therein, as shown. A gas supply pipe 54 extends upwardly from the burner ring through drum 85 11 and may be connected at its upper end in any suitable manner with a source of gas.

The operation is as follows:

The operator places a circular blank A formed of paper, muslin, or other fabric, 90 upon the rubber cushion 10, with the blank-positioning pin 5 extending through a central aperture B formed in the blank. The treadle 23 is then depressed and the blank-supporting table 2 rotated by the handle 8 95 to bring the medial lines of the radially extending petal portions of the blanks directly under the rollers 16 prior to the engagement of the rollers with the petals C. It will be understood that post 19 and disk 18 are 100 previously adjusted, as hereinbefore described, so that the initial points of engagement of the rollers with the petals will be at the outer ends of the petals. After the engagement of the rollers with the petals, 105 the continued upward movement of the table will rock the fingers inwardly about the pivots 15, thus causing the rollers to travel inwardly along radially converging lines longitudinally of the petals. The weight of 110 the fingers 14, disk 18, post 19, lever 48 and connected parts, will press the rollers 16 into the soft rubber disk 10 and said rollers will thus force the petals down into the disk as they travel inwardly, crimping or crinkling the petals transversely and simultaneously curling the petals and scoring the same longitudinally along closely adjacent parallel lines. As the fingers swing inwardly and upwardly the disk 18 and post 115 19 are forced upwardly, imparting a uniform upward movement to the rollers and, through the lever 48 and its connected links and rock arms, also swinging the treadle 35 rearwardly. As the rollers complete their 120 scoring, curling and crinkling movement, the operator presses one foot against treadle 35 to hold the same in its rearwardly shifted position, and then releases treadle 23, whereupon the blank support will move down- 130

- wardly while the scoring devices will be held in their elevated position and the scored, curled and crinkled blank may be readily removed without injury thereto.
- 5 After the removal of the blank the treadle 35 is released to permit the scoring devices to return to their normal position. It will be obvious that treadle 35 may be depressed to elevate the scoring devices while a blank
- 10 is being placed upon the blank support, if desired, in order to give more free access to the blank support, the treadle in this case being released prior to the depression of treadle 23.
- 15 The extent of the crinkling action may be varied, or such action eliminated by employing cushions of different degrees of resiliency. If a hard disk or cushion 10 is employed, or the blank placed directly on table 2, the crinkling action will be practically or entirely eliminated and the petals will be merely scored and curled. The disk 18 controls the movement of fingers 14 and insures a uniform travel of the rollers.
- 20 25 It will be obvious that a suitable spring may be employed for increasing the pressure upon the rollers 16, but it has been found in practice that the weight of the parts above referred to is amply sufficient for this purpose.
- 30 It will be obvious also that various forms of scoring rollers may be employed, although I prefer to employ grooved rollers to score the petals so as to simulate the vein or longitudinal rib found in the petals of most flowers. It will also be obvious that the rollers may be omitted and the fingers formed with grooved or other forms of scoring ends or portions, if desired.
- 35 What I claim is:
- 40 1. In a machine for shaping blanks having a circular series of radially extending petals, the combination of a blank support provided with a blank-centering projection, a circular series of scoring devices, means
- 45 whereby the support may be rotatably adjusted manually to position the petals simultaneously beneath the scoring devices, and means whereby the scoring devices may be shifted radially of the blank support
- 50 while in engagement therewith.
- 55 2. In a machine of the class set forth, the combination of a circular series of scoring devices, means for supporting the scoring devices to move toward and from a common center, a blank support mounted below the series of scoring devices rotatably adjustable to position a circular series of radially extending petals simultaneously beneath the scoring devices, means for elevating the support, and means controlled by the upward movement of the blank support while in contact with the scoring devices for causing said devices to move longitudinally of the petals.
- 60 65 3. In a machine for shaping a plurality of
- diverging petals, the combination of a series of scoring devices, a petal support rotatably adjustable to position the petals simultaneously beneath the scoring devices, means for elevating the support, and means controlled by the upward movement of the support while in engagement with the scoring devices for causing said devices to move simultaneously longitudinally of the petals.
- 70 4. In a machine of the class set forth, the combination of a circular series of scoring devices, stationary means for pivotally supporting said devices at one end to swing toward and from a common center, a rotatably and reciprocably mounted blank support normally located below the free ends of said devices, and manually adjustable around its axis of rotation to position the petal portions of a blank under the free ends of the series of scoring devices, and means for reciprocating the blank support toward and from said supporting means, the free ends of said scoring devices being movable inwardly along radially converging lines by the blank support upon continued movement of the blank support toward said stationary supporting means after engagement of the blank support with the free ends of said devices.
- 75 5. In a machine of the class set forth, the combination of a stationary support, a circular series of depending inwardly bowed fingers pivotally held at their upper ends to said stationary support to swing toward and from a common center and provided with scoring means at their lower ends, a vertically reciprocable blank support below said series of fingers adapted to engage the scoring means when elevated to rock the fingers about their pivots and cause the scoring means to traverse the upper surface of the support, said fingers being provided with inwardly extending arms adjacent their pivots and a disk movable vertically relatively to said stationary support and having its edge extending between said arms and the bowed portions of the fingers.
- 80 85 6. In a machine of the class set forth, the combination of a stationary support, a circular series of depending inwardly bowed fingers pivotally held at their upper ends to said stationary support to swing toward and from a common center and provided with scoring means at their lower ends, a vertically reciprocable blank support below said series of fingers adapted to engage the scoring means when elevated to rock the fingers about their pivots and cause the scoring means to traverse the upper surface of the support, said fingers being provided with inwardly extending arms adjacent their pivots, a disk movable vertically relatively to said stationary support and having its edge extending between said arms and the bowed portions of the fingers, and means for limit-
- 90 95 100 105 110 115 120 125 130

ing the downward movement of said disk to maintain the free ends of the fingers inside the vertical plane of the pivotal points of the fingers.

5 7. In a machine of the class set forth, the combination of a stationary support, a circular series of depending inwardly bowed fingers pivotally held at their upper ends to said stationary support to swing toward 10 and from a common center and provided with scoring means at their lower ends, a vertically reciprocable blank support below said series of fingers adapted to engage the scoring means when elevated to rock the 15 fingers about their pivots and cause the scoring means to traverse the upper surface of the support, said fingers being provided with inwardly extending arms adjacent their pivots, a disk movable vertically relatively to said stationary support and having its edge extending between said arms and the bowed portions of the fingers, and 20 adjustable means for limiting the downward movement of said disk.

25 8. In a machine of the class set forth, the combination of a stationary support, a circular series of depending inwardly bowed fingers pivotally held at their upper ends to said stationary support to swing toward 30 and from a common center and provided with scoring means at their lower ends, a vertically reciprocable blank support below said series of fingers adapted to engage the scoring means when elevated to rock the 35 fingers about their pivots and cause the scoring means to traverse the upper surface of the support, said fingers being provided with inwardly extending arms adjacent their pivots, a disk movable vertically relatively to said stationary support and having its edge extending between said arms and the bowed portions of the fingers, means 40 for limiting the downward movement of said disk to maintain the free ends of the fingers inside the vertical planes of the pivotal points of the fingers, and manually operable means for elevating said disk independently of the blank support.

50 9. In a machine of the class set forth, the combination of a stationary support, a circular series of depending inwardly bowed fingers pivotally held at their upper ends to said stationary support to swing toward and from a common center and provided 55 with scoring means at their lower ends, a vertically reciprocable blank support below said series of fingers adapted to engage the scoring means when elevated to rock the fingers about their pivots, said fingers being 60 provided with inwardly extending arms adjacent their pivots, a disk movable vertically relatively to said stationary support and having an upwardly and inwardly beveled outer edge engaged by the inner ends 65 of said arms, and manually operable means

for elevating said disk independently of the blank support.

10. In a machine of the class set forth, the combination of a stationary support, a circular series of depending inwardly bowed fingers pivotally held at their upper ends to said stationary support to swing toward and from a common center and provided with scoring means at their lower ends, a vertically reciprocable blank support below 70 said series of fingers adapted to engage the scoring means when elevated to rock the fingers about their pivots and cause the scoring means to traverse the upper surface of the support, said fingers being provided 75 with inwardly extending arms adjacent their pivots, a disk movable vertically relatively to said stationary support and having its edge extending between said arms and the bowed portions of the fingers, a 80 treadle operatively connected with said disk to move in unison therewith, and a treadle operatively connected with the blank support for reciprocating said support.

11. In a machine of the class set forth, the combination of a stationary support, a circular series of depending inwardly bowed fingers pivotally held at their upper ends to said stationary support to swing toward and from a common center and provided with 90 scoring means at their lower ends, a vertically reciprocable blank support below said series of fingers adapted to engage the scoring means when elevated to rock the fingers about their pivots and cause the scoring means to traverse the upper surface of the support, said fingers being provided with inwardly extending arms adjacent their pivots, a disk movable vertically relatively to said 95 stationary support and having its edge extending between said arms and the bowed portions of the fingers, a treadle operatively connected with said disk to move in unison therewith, a treadle operatively connected with the blank support for reciprocating said 100 support, and adjustable means for limiting the vertical movement of the disk.

12. In a machine of the class set forth, the combination of a stationary support, a circular series of depending fingers pivotally held at their upper ends to said stationary support to swing toward and from a common center, means connected with all of said fingers for normally swinging the fingers outwardly, means for limiting the outward movement of the fingers to prevent the free ends thereof moving outwardly beyond vertical planes through the pivots of the fingers, circumferentially - grooved scoring rollers held to the lower ends of the fingers, a blank support below said series of fingers adapted to engage the rollers and rock the fingers inwardly and upwardly, means for raising and lowering the blank support, and means connected with the finger spreading 115 120 125 130

means adapted to shift said means to swing the fingers inwardly and upwardly about their pivots relatively to the stationary support independently of movement of the blank support.

13. In a machine of the class set forth, the combination of a stationary scoring device support, a circular series of scoring devices pivotally held to said stationary support to swing toward and from a common center, means for normally forcing the free ends of said scoring devices downwardly and outwardly, means for limiting the extent of the downward and outward movement of the 10 free ends of the scoring devices to points within the vertical planes of the pivotal points of said devices, a blank support below said devices adapted to engage the free ends thereof and rock the devices inwardly and 15 upwardly, and means for raising and lowering the blank support.

14. In a machine of the class set forth, the combination of a stationary scoring device support, a circular series of scoring devices pivotally held to said stationary support to swing toward and from a common center, controlling means for said devices movable relatively to said support and operatively connected to cause the 20 devices to swing about their pivots in unison

inwardly and outwardly, means for limiting the extent of movement of said controlling means relatively to the stationary scoring device support, a blank support below said devices, means for raising the blank support to 35 cause the same to engage and rock the scoring devices inwardly and upwardly, and means connected with said controlling means for holding the scoring devices in their inwardly and upwardly shifted position when 40 the blank support is lowered.

15. In a machine of the class set forth, the combination of a stationary scoring device, a circular series of scoring devices pivotally held to said stationary support to swing to- 45 ward and from a common center, a vertically reciprocable controller mounted on said stationary support and connected with the scoring devices to cause the same to swing in unison, means for limiting the extent of 50 vertical movement of said controller, manually operable means for raising and lowering said controller, a rotatably adjustable blank support below the scoring devices, manually operable means for raising and 55 lowering the blank support, and blank centering means on the blank support.

This specification signed this twelfth day of May, A. D. 1919.

ALWIN J. SCHWARZENBACH.
